(57) **CLAIM**

The ornamental design for a solar light, as shown and described.

DESCRIPTION

FIG. 1 is a three-dimensional view of a solar light in accordance with my invention;

FIG. 2 is a front view of the solar light shown in FIG. 1; FIG. 3 is a top view of the solar light shown in FIG. 1; and, FIG. 4 is a bottom view of the solar light shown in FIG. 1. The broken lines shown on the drawings are for illustrative purposes only and form no part of the claimed design.
